(57) **CLAIM**

The ornamental design for a wooden textured key fob, as shown and described.

DESCRIPTION

FIG. 1 is a top perspective view of the wooden textured key fob according to the present invention.

FIG. 2 is a front elevational view of the wooden textured key fob of FIG. 1.

FIG. 3 is a back elevational view of the wooden textured key fob of FIG. 1.

FIG. 4 is a right-side elevational view of the wooden textured key fob of FIG. 1.

FIG. 5 is a left-side elevational view of the wooden textured key fob of FIG. 1.

FIG. 6 is a top plan view of the wooden textured key fob of FIG. 1; and,

FIG. 7 is a bottom plan view of the wooden textured key fob of FIG. 1.

The dashed lines in the figures are for environmental purposes only, and form no part of the claimed design.

1 Claim, 7 Drawing Sheets
